[57] CLAIM

The ornamental design for a drinking glass, substantially as shown and described.

DESCRIPTION

FIG. 1 is a front elevational view of a drinking glass embodying my new design.

FIG. 2 is a right side elevational view thereof, the side opposite being a mirror image thereof;

FIG. 3 is a rear elevational view thereof.

FIG. 4 is a vertical sectional view taken along line 4—4 of FIG. 2.

FIG. 5 is a top plan view thereof.

FIG. 6 is a horizontal sectional view taken along line 6—6 of FIG. 4.
